HOT GAS APPARATUS INCLUDING A
REGENERATORFrits Karel du Pré, Tarrytown, N. Y., assignor to
Hartford National Bank & Trust Co., Hartford,
Conn., as trustee

Application August 7, 1947, Serial No. 767,305

20 Claims. (Cl. 60—24)

1

My invention relates to hot-gas apparatus of the type which utilizes a regenerator through which a working medium flows in an alternate manner.

This application is a continuation-in-part of my copending application Ser. No. 674,492 filed June 5, 1946, now abandoned.

As my invention is particularly useful in hot-gas external combustion engines, I shall describe the same in this connection. However, my invention is not limited to such engines but is applicable to other types of hot-gas apparatus such as a refrigeration machine operating on the reverse principle of the hot-gas cycle and utilizing a regenerator which alternately removes and replaces thermal energy contained in a working medium in the engine as the medium moves through a predetermined cycle.

Although hot-gas apparatus has been known for many years and has had a very limited commercial success, such apparatus has to a large extent gone out of use in recent years. This has been due mainly to the fact that such apparatus, as compared for instance to internal combustion engines, had a large weight per horsepower, had a relatively low speed and a low overall efficiency. Because of these factors it was thought that such engines were impractical, particularly in the larger sizes and thus apparently there has been little work on the same within recent years. Although there has been some suggestions as to improving the general design of said engines, as far as I am aware such suggestions have not lead to the production of a commercially successful engine.

The main object of my invention is to increase the thermal efficiency of hot-gas apparatus.

A further object of my invention is to increase the operating speed of hot-gas apparatus.

Another object of my invention is to increase the horsepower output per pound of engine weight of such hot-gas apparatus.

Still another object of my invention is to provide a hot-gas apparatus capable of operating at an increased temperature difference between the heated and the cooled end of the apparatus by virtue of an improved regenerator.

These and further objects of the invention will become apparent as the specification progresses.

The hot-gas apparatus according to the invention comprises a hot chamber connected to a cold chamber through a regenerator comprising a mass of finely divided filling material which is uniformly distributed through a portion of the regenerator space and has a surface area per unit

2

volume of the space occupied between about 25 cm^2/cm^3 to 750 cm^2/cm^3 , preferably between about 100 cm^2/cm^3 and 200 cm^2/cm^3 . Furthermore the mass of filling material has a thickness

5 in the direction of flow of the working medium between about 0.3 cm. and 8 cm., preferably between about 0.8 cm. and 4 cm. in the case of a hot-gas engine and preferably between about 5 cm. and 8 cm. in the case of a refrigerating ma-

10 chine operating on the reverse principle of the hot-gas cycle, a heat capacity between about three to twenty-five times the heat capacity of the working medium flowing through the regenerator during one stroke of the engine and a total vol-

15 ume of the voids less than about five times, preferably less than about three times the mean volume of the working medium passing through the regenerator in one direction during each cycle.

In addition the regenerator has a space factor 20 between about 3 and 60, preferably about 6 to 25. The filling material furthermore has a low overall heat conductivity. By the expression

25 "heat capacity" I mean the quantity of heat needed to increase the temperature of the filling mass 1° centigrade. The expression "space factor" means the ratio between the overall volume occupied by the regenerator to the volume occupied by the material of the filling mass of the regenerator.

30 In constructing a regenerator having values within the ranges as outlined above, it will not in general be feasible to utilize a combination of the extremes of the values listed in order to obtain the best results. For example, if it is found

35 desirable to use a maximum value of surface area per unit volume of space occupied, then intermediate values of regenerator thickness, and/or heat capacity, will generally serve best in the combination. If such a procedure is not followed

40 in the construction of the regenerator, the operating efficiency of the regenerator although good, may not be as high as when using the proper combination of the values within the ranges specified.

45 In one embodiment of my invention I use as the filling material, metallic filamentary material, the average cross-sectional area of the filaments being about $1 \times 10^{-6} \text{ cm}^2$ to $300 \times 10^{-6} \text{ cm}^2$, preferably $3 \times 10^{-6} \text{ cm}^2$ to $40 \times 10^{-6} \text{ cm}^2$.

50 In another embodiment of my invention I utilize a filling material comprised of glass, asbestos or cotton fibers which are sandwiched between two layers of porous material which serve to keep 55 the fibers in their given location.

By way of illustration, a form of my invention is shown in the attached drawing in which:

Fig. 1 is a longitudinal section view of a hot-gas apparatus in accordance with the invention.

Fig. 2 is a partial schematic sectional drawing illustrating the position of a regenerator in a hot-gas apparatus.

Fig. 3 is a cross sectional view of a regenerator.

Fig. 4 is another cross sectional view of a regenerator.

Referring to Fig. 1 of the drawing the numeral 10 indicates an enclosed chamber having heat insulating walls, this chamber serving as the heating chamber when the apparatus is used as a hot-gas engine, or serving as the cooling chamber when the apparatus functions as a refrigerator and operates on the reverse principle of the hot-gas cycle. A displacer 11 and a piston 13 operate on a working medium, such as air, hydrogen, helium, nitrogen and the like, within the engine and are each connected to a crankshaft 12, in such a manner, that changes in the volume of the space above the displacer and of the space above the piston are displaced about 90° relative to each other. As can be seen from this structural arrangement the working medium alternately flows between the space above the displacer and the space above the piston in a closed path and must pass through a regenerator 14 which is located in this path. The space between the top of the displacer 11 and the regenerator 14 is at a high temperature when the apparatus is used as a hot-gas engine and for present purposes I will designate this space as the "hot chamber," while the space between the regenerator 14 and the top of the piston 13 is at a lower temperature and for present purposes I will designate this space as the "cold chamber." To prevent heat losses due to a conduction of heat through the housing of the regenerator and the filling mass itself it is advisable that both of them consist of a material with low heat conductive properties. A crankcase 15 is provided, which crankcase is generally made fluid tight and contains lubricating oil, and furthermore serves as a reservoir for the working medium of the cycle, the working medium being usually introduced into the cycle through a conduit and valve system (not shown) which interconnects the crankcase with the space above the piston.

When the hot-gas apparatus shown in Fig. 1 is used as a hot-gas engine, the power which is developed is delivered by the crankshaft 12, whereas, when the said apparatus is used as a refrigerator, power is applied to the crankshaft by means of a prime mover, for example, a motor (not shown).

Fig. 2 illustrates the position of the regenerator shown as 16 relative to the hot chamber shown as 17 and the cold chamber shown as 18. It is to be noted that the cross sectional area of the regenerator is preferably made equal to that of the passageway interconnecting the hot and cold chambers and is positioned so that all of the working medium flowing between the respective chambers must flow through the regenerator.

A regenerator 19 according to a preferred embodiment of my invention is shown in Fig. 3. In this instance the regenerator mass comprises uniformly-distributed filling material, such as fine metallic wire of a ferro-chromium alloy or of a ferro-nickel-chromium alloy. I have found that if the ratio of the surface area of the regenerator filling to its volume is in the range of about

25 cm.²/cm.³ to about 750 cm.²/cm.³ preferably between about 100 cm.²/cm.³ and 200 cm.²/cm.³, and if the individual filaments have a cross sectional area within the range of about 1×10^{-6} cm.² to about 300×10^{-6} cm.² preferably about 3×10^{-6} cm.² to 40×10^{-6} cm.², the rate of heat transfer is directly proportional to the flow velocity of the medium, a fact which is quite unexpected in view of the literature concerned with heat phenomenon, and has the advantage that the regenerator efficiency will be practically independent of engine speed. Furthermore, I have discovered that the regenerator filling material must be uniformly distributed, whether the pattern be regular or random, if the regenerator is to provide satisfactory operation. By uniformly distributed it is meant that each unit of the regenerator filling mass, regardless of location within the regenerator, will be comparable with respect to average density distribution.

The regenerator mass in the preferred embodiment of my invention as shown by Fig. 3 has a heat capacity of about five times that of the heat capacity of the working medium passing through the regenerator in one direction during each cycle. Quite unexpectedly I have found that it is possible to use a factor as low as three times instead of the above mentioned preferred factor, and still have the regenerator operate at a high efficiency. Likewise I have found that the total volume of the voids in the regenerator must be less than about five times and preferably less than about three times, the piston displacement of the apparatus. Also the regenerator has a space factor between about 3 and 60, preferably between about 6 to 25.

The thickness of the regenerator mass in the direction of flow of the medium must, as previously pointed out, be within the range of about 0.3 cm. minimum to about 3 cm. maximum preferably between about 0.8 cm. and 4 cm. If the minimum thickness is less than the said minimum, then regardless of the cross sectional area of the regenerator, an insufficient transfer of heat between the regenerator and the working medium will take place, and a high speed engine of high operating efficiency would not be realized. When the regenerator has a thickness greater than the above stated maximum, frictional losses of the working medium similarly reduce the efficiency of the hot-gas apparatus and preclude the attainment of a high speed hot-gas apparatus. I have found that in order to produce a satisfactory high speed hot-gas apparatus the maximum permissible power loss through the regenerator must be less than about 20%, preferably less than 10%.

The efficiency of a regenerator is understood to mean the relative ability of the regenerator to change the temperature of the flow medium to a temperature corresponding to the temperature of that end of the apparatus toward which the medium is flowing. The regenerator shown by Fig. 3 which embodies the principles of our invention, exhibits an operating efficiency of about 95% and better. With regenerators having such a high efficiency and incorporating the principles of our invention, hot-gas apparatus can be made to operate at a high thermal efficiency and at speeds of 2000 R. P. M. and higher.

In Fig. 4 another form of a regenerator is illustrated. The number 20 indicates a filling material made from substances such as glass fiber, asbestos fiber, or other finely-divided materials which withstand the operating temperatures

used. When the apparatus shown in Fig. 1 is used as a refrigerator, the filling 20 may also consist of cotton wadding. The principles of my invention are applied in the design of such a regenerator mass, that is, the surface area per unit volume of the space occupied is between about $25 \text{ cm}^2/\text{cm}^3$ to $750 \text{ cm}^2/\text{cm}^3$, an average cross sectional area of individual filaments being about $1 \times 10^{-6} \text{ cm}^2$ to $300 \times 10^{-6} \text{ cm}^2$, etc. With such a form of filling material I have overcome the disadvantages caused by the tendency of the material to break into small particles due to their rather brittle nature by utilizing layer 21—21 of porous material, such as a fine wire mesh pad placed on each side of the brittle filling mass, such layers 21—21 also serving to retain the mass 20 in its original position and shape. A regenerator such as shown in Fig. 4 is particularly useful when the hot-gas apparatus of the invention is used as a refrigerator, wherein the temperatures of the working medium are at a relatively low level.

While I have shown and described particular embodiments of my invention I do not wish to be limited thereto since variations may be made in form without departing from the true spirit of the invention.

What I claim is:

1. In a hot-gas apparatus operating with a given amount of flow medium and having cylinder means defining a hot chamber and a cold chamber, a housing having an inlet opening and an outlet opening interconnecting said chambers; a heat regenerator comprising a mass of finely divided filling material comprising elements having a cross sectional area within the range of about $1 \times 10^{-6} \text{ cm}^2$ to about $300 \times 10^{-6} \text{ cm}^2$, said mass having a ratio of surface area to volume within the range of about $25 \text{ cm}^2/\text{cm}^3$ to $750 \text{ cm}^2/\text{cm}^3$, being about 0.3 cm. minimum to about 8 cm. maximum in thickness, having a total heat capacity greater than about three times the heat capacity of the flow medium passing in one direction through said regenerator, and having a total volume of voids less than about five times that of the mean volume of the flow medium passing in one direction through said regenerator.

2. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross sectional area within the range of about $3 \times 10^{-6} \text{ cm}^2$ to about $40 \times 10^{-6} \text{ cm}^2$, said mass having a ratio of surface area to volume within the range of about $100 \text{ cm}^2/\text{cm}^3$ to $200 \text{ cm}^2/\text{cm}^3$, being about 0.8 cm. minimum to about 4 cm. maximum in thickness, having a total heat capacity greater than about five times the heat capacity of the flow medium passing in one direction through said regenerator, and having a total volume of voids less than about three times that of the mean volume of the flow medium passing in one direction through said regenerator.

3. In a hot-gas apparatus operating with a given amount of flow medium and having cylinder means defining a hot chamber and a cold chamber, a housing having an inlet opening and an outlet opening interconnecting said chambers; a heat regenerator comprising a mass of finely divided filling material comprising elements having a cross sectional area within the range of about $1 \times 10^{-6} \text{ cm}^2$ to about $300 \times 10^{-6} \text{ cm}^2$, said mass

having a ratio of surface area to volume within the range of about $25 \text{ cm}^2/\text{cm}^3$ to $750 \text{ cm}^2/\text{cm}^3$, being about 0.3 cm. minimum to about 8 cm. maximum in thickness, having a total heat capacity greater than about three times the heat capacity of the flow medium passing in one direction through said regenerator, and having a total volume of voids less than about five times that of the mean volume of the flow medium passing in one direction through said regenerator, said filling material consisting of a ferro-alloy selected from the group consisting of ferro-chromium and ferro-nickel-chromium.

4. In a hot-gas apparatus operating with a given amount of flow medium and having cylinder means defining a hot chamber and a cold chamber, a housing having an inlet opening and an outlet opening interconnecting said chambers; a heat regenerator comprising a mass of finely divided filling material comprising elements having a cross sectional area within the range of about $1 \times 10^{-6} \text{ cm}^2$ to about $300 \times 10^{-6} \text{ cm}^2$, said mass having a ratio of surface area to volume within the range of about $25 \text{ cm}^2/\text{cm}^3$ to $750 \text{ cm}^2/\text{cm}^3$, being about 0.3 cm. minimum to about 8 cm. maximum in thickness, having a total heat capacity greater than about three times the heat capacity of the flow medium passing in one direction through said regenerator, and having a total volume of voids less than about five times that of the mean volume of the flow medium passing in one direction through said regenerator, said filler consisting of a material of low heat conductivity selected from the group consisting of glass, asbestos and cotton fibers.

5. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross sectional area within the range of about $1 \times 10^{-6} \text{ cm}^2$ to about $300 \times 10^{-6} \text{ cm}^2$, said mass having a ratio of surface area to volume within the range of about $100 \text{ cm}^2/\text{cm}^3$ to $200 \text{ cm}^2/\text{cm}^3$, being about 0.3 cm. minimum to about 8 cm. maximum in thickness, having a total heat capacity greater than about three times the heat capacity of the flow medium passing in one direction through said regenerator and having a total volume of voids less than about five times that of the mean volume of the flow medium passing in one direction through said regenerator.

6. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross sectional area within the range of about $1 \times 10^{-6} \text{ cm}^2$ to about $300 \times 10^{-6} \text{ cm}^2$, said mass having a ratio of surface area to volume within the range of about $25 \text{ cm}^2/\text{cm}^3$ to $750 \text{ cm}^2/\text{cm}^3$, being about 0.8 cm. minimum to about 4 cm. maximum in thickness, having a total heat capacity greater than about three times the heat capacity of the flow medium passing in one direction through said regenerator and having a total volume of voids less than about five times that of the mean volume of the flow medium passing in one direction through said regenerator.

7. In a hot-gas apparatus operating with a given amount of flow medium and comprising

having a total volume of voids less than about three times that of the mean volume of the flow medium passing in one direction through said regenerator.

15. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross sectional area within the range of about 3×10^{-6} cm.² to about 40×10^{-6} cm.², said mass having a ratio of surface area to volume within the range of about 25 cm.²/cm.³ to 750 cm.²/cm.³, being about 0.8 cm. minimum to about 4 cm. maximum in thickness, having a total heat capacity greater than about three times the heat capacity of the flow medium passing in one direction through said regenerator and having a total volume of voids less than about five times that of the mean volume of the flow medium passing in one direction through said regenerator.

16. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material, said mass having a ratio of surface area to volume within the range of about 100 cm.²/cm.³ to 200 cm.²/cm.³, being about 0.3 cm. minimum to about 8 cm. maximum in thickness, having a total heat capacity greater than about five times the heat capacity of the flow medium passing in one direction through said regenerator, and having a total volume of voids less than about three times that of the mean volume of the flow medium passing in one direction through said regenerator, said filling material having a space factor of about 6 to about 25.

17. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material, said mass having a ratio of surface area to volume within the range of about 25 cm.²/cm.³ to 750 cm.²/cm.³, being about 0.3 cm. minimum to about 8 cm. maximum in thickness, having a total heat capacity greater than about three times the heat capacity of the flow medium passing in one direction through said regenerator and having a total volume of voids less than about five times that of the mean volume of the flow medium passing in one direction through said regenerator, said filling material having a space factor of about 3 to about 60.

18. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross sectional area within the range of about 3×10^{-6} cm.² to about 40×10^{-6} cm.²,

said mass having a ratio of surface area to volume within the range of about 100 cm.²/cm.³ to 200 cm.²/cm.³, being about 0.8 cm. minimum to about 4 cm. maximum in thickness, having a total heat capacity greater than about three times the heat capacity of the flow medium passing in one direction through said regenerator, and having a total volume of voids less than about three times that of the mean volume of the flow medium passing in one direction through said regenerator, said filling material made from a ferro-alloy selected from the group consisting of ferro-chromium or ferro-nickel-chromium.

19. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material comprising elements having a cross-sectional area within the range of about 3×10^{-6} cm.² to about 40×10^{-6} cm.², said mass having a ratio of surface area to volume within the range of about 100 cm.²/cm.³ to 200 cm.²/cm.³, being about 0.8 cm. minimum to about 4 cm. maximum in thickness, having a total heat capacity greater than about three times the heat capacity of the flow medium passing in one direction through said regenerator, and having a total volume of voids less than about three times that of the mean volume of the flow medium passing in one direction through said regenerator, said filler consisting of a material of low heat conductivity selected from the group consisting of glass, asbestos and cotton fibers.

20. In a hot-gas apparatus operating with a given amount of flow medium and comprising cylinder means defining a hot chamber and a cold chamber, a housing having an inlet opening and an outlet opening interconnecting said chambers; a heat regenerator comprising a mass of finely divided filling material, said mass having a ratio of surface area to volume within the range of about 25 cm.²/cm.³ to 750 cm.²/cm.³, being about 0.3 cm. minimum to about 8 cm. maximum in thickness, having a total heat capacity greater than about three times the heat capacity of the flow medium passing in one direction through said regenerator and having a total volume of voids less than about five times that of the mean volume of the flow medium passing in one direction through said regenerator, said filling material being of uniform distribution, and having a space factor between about 3 and 60, and further arranged so that all of said flow medium passes through said regenerator.
